UNITED STATES PATENT OFFICE.

JOHN W. CHASE, OF BANGOR, MAINE.

CALCULATING OR COMPUTING MACHINE.

Application filed July 24, 1922. Serial No. 577,109.

To all whom it may concern:

Be it known that I, JOHN W. CHASE, a citizen of the United States, residing at Bangor, in the county of Penobscot and State of Maine, have invented a certain new and useful Calculating or Computing Machine, of which the following is a specification.

My invention relates to a certain new and useful machine or apparatus for effecting computations and the invention generically seeks to provide a machine for mechanically effecting numerical or other computations wherein the range of computation possible is exceptionally great in proportion to the size of the mechanism necessary to provide that range of computation.

More specifically the invention resides in the provision of a simple, inexpensive, practical and exceedingly compact machine for making calculations of a desired nature, wherein is embodied a housing having an observation opening or window through which is visible the whole or a portion of a plurality of hollow cylinders loosely mounted upon a central shaft having bearings within said housing, said cylinders being mounted one within another and each having a longitudinal slot in its face, the slots of the several cylinders being capable of being brought into register with one another and with the said observation opening and suitable indicia upon the external face of each of the cylinders; the invention also resides in the provision of means for effecting a complete rotation of the central shaft, the provision of a visible indicator controlled locking and releasing means for securing together the central shaft and such of the cylinders as it is desired to rotate and for locking, to a stationary position, such of the cylinders as it is desired should remain stationary and for likewise releasing such cylinders from the locked position; the invention also resides in the provision of a radially adjustable indicator bar having indicia thereon and designed to cover such of the indicia upon the selected rotative cylinder as should not be visible and for attracting the observation to such of said indicia as is necessary to the desired mechanically obtained calculation.

The invention furthermore has for its object the provision of an apparatus of the kind stated in which the indicia on the several cylinders are arranged in major and

minor columns and spaces, each major space having associated with it a plurality of horizontal and vertical columns, the number of horizontal columns and the number of vertical columns of each minor set of indicia corresponding in number to the number of slats on the indicator and to the number of locations on those slots, while all of the major indicia spaces cooperate with a single window in the indicator, whereby it is possible to keep the indicia of the indicator comparatively widely separated one from another in a small area or compass to thereby facilitate readings, while at the same time permitting a vastly greater number of indicating units being placed on the cylinders of a given size than would otherwise be possible; or in other words, it is an object of my invention to make the apparatus as small in size as is possible and yet maintain as large a separation between the various characters to be observed as possible in order to facilitate rapid calculations and prevent confusion of numbers which would occur were the units arranged on a small scale close together.

With the above objects in view and others which will be clear to those skilled in the art, the invention resides in those novel features of construction, combination and arrangement of parts, all of which will be first fully described and then be specifically pointed out in the appended claims, reference being had to the accompanying drawings, in which:

Figure 1 is a detail perspective view of a complete tabulating machine embodying my invention.

Figure 2 is a central vertical longitudinal section of the left hand end and medial portion of the machine, parts being broken out and contracted.

Figure 3 is a view, similar to Figure 2, of the right hand end of the machine.

Figure 4 is a detail cross section taken on the line 4—4 of Figure 2 looking in the direction of the arrow.

Figure 5 is a detail plan view of the radially adjustable indicator bar, parts being broken out and the ends contracted.

Figure 6 is a detail section illustrating the manner of adjusting the indicator bar.

Figures 7 and 8 are diagrammatic cross sections of a portion of the cylinders illustrating certain adjusted positions of the indicator bar.

Figure 9 is a diagrammatic view illustrating the operation of the cylinder locking keys hereinafter referred to.

Figure 10 is a diagrammatic view illustrating the release of the indicator bar to an exemplary plane of marking of the external faces of the cylinder, whereby computation by multiplication is effected in a manner hereinafter referred to.

10 Figure 11 is a detail section illustrating one manner in which the cylinders may be constructed.

In the drawings like numerals of reference indicate like parts in all of the figures and the cylinders are hereinafter described and illustrated as being marked peculiarly to enable or effect computation by multiplication, although it is to be understood that this is done solely to illustrate one means of 15 utilizing my tabulating mechanism as it is evident that other and different classes of calculations may be effected by suitably changing the indicia or markings upon the external faces of the cylinders, without departing from the scope of the invention, as for example the tabulation or indicia on the cylinders may be designed to effect computations by division or subtraction, if desired.

30 Referring now to the drawings, 1 represents a suitable housing for the mechanism. It includes an angled face 2 which is provided with an observation opening 3, the same being covered with any suitable transparent substance, thereby permitting the operator to view the desired portions only of the mechanism within the housing.

Upon a hollow central shaft 4, which is suitably mounted in end bearings 5-5 that 40 are fastened to the housing ends, are loosely mounted a plurality of cylinders closely nested one within another and capable of individual independent rotary motion. These cylinders are constructed of suitable 45 light, thin material with the ends closed. The ends or hub portions of the cylinder may be substantially thicker than the circumferential portions. It is to be understood that the cylinders must be constructed 50 one over another in sequence from the innermost one thereof to the outermost one thereof and in the simple illustration thereof in the drawings, the cylinders (ten being shown) are represented by the numerals 6, 55 7, 8, 9, 10, 11, 12, 13, 14 and 15 in the order of their construction above described. The cylinders may be made with one end integral with the barrel of the cylinder and the other end plugged in and held by set screws 60 or other suitable means (see Figure 11). Each cylinder has key or locking slots 16 provided in the hub ends thereof, which are adapted to register with the corresponding slots of the other cylinders. The cylinders 65 also have longitudinal observation slots 17

at their peripheries which are capable of registering one with another in the manner and for the purposes later understood. The circumferential faces of the cylinders are marked with the usual indicia to cooperate 70 with the indicating mechanism in effecting the desired calculations.

Cooperating with the registering longitudinal observation slots 17 is an indicator bar 18 having a series (three being shown) 75 of indicating slats 19 so positioned as to provide a corresponding number of observation spaces or slots 20 below each of the slats and the bar 18 near its left hand end, is provided with an observation aperture or window 21. At each extreme end, projected beyond the outermost cylinder, the bar has secured thereto a casting 22 which is mounted with the flat portion thereof in radially slidable engagement with a retaining bearing 23 secured to the housing portion 2 and each of said castings also includes a portion that carries a camming roller 24 for purposes later understood (see Figures 5 and 6).

As previously explained, the illustration herein made is of a multiplication type of calculator and in the same I make provision in the compact arrangement of mechanism shown for the multiplication of any number from one to one hundred and fifty times any number from one to one thousand so that the sums may be multiplied up to a total of one hundred and fifty thousand. The numerical arrangement for effecting 100 this result will now be described and then a description given for the mechanism of effecting that result.

The indicating slats 19 of the bar 18 have marked thereon, in any suitable manner, the inscription numbers ranging consecutively from one to one hundred and fifty, as follows to wit: one to fifty on the topmost one of the slats, fifty-one to one hundred on the medial one thereof and one hundred and one to one hundred and fifty on the lowermost one thereof (see Figure 5). These numbers are indicative of the number being multiplied, in this way—due to the peculiar arrangement of the indicia on the circumferential faces of the cylinders (next to be described), the manner of mechanically manipulating said cylinders and the arrangement of the longitudinal slots in said cylinders, it is possible, and such therefore is 110 the practice, for the operator to glance below the indicative number on the particular slat 19 upon which it is found, and there find the desired total. Thus an operator 115 who wishes to find the result of one hundred and forty-six times twelve for example, would, after manipulating the mechanism properly to bring the major number one hundred and forty-six of the cylinder 7 into 120 register with the observation window 21, 125

glance below the numeral twelve on the top-most indicator slat 19 and there find the total to be correctly one thousand seven hundred and fifty-two.

5 The manner of marking the cylinder and the cooperative relation of said marking with the indicator bar markings described immediately above now follows:—The positioning of the markings upon the cylinders 10 is regulated by the lateral limits of the innermost or smaller cylinder so that the markings as to spacing are in perfect radial alignment. The distance around the circumference of each cylinder from one edge of 15 the slot 17 to the other edge thereof is divided into one hundred (plus one for each observation slot more than one in indicator bar 18) equal horizontal spaces by lines 25 inscribed upon the cylinder horizontally to 20 clearly mark such spaces. As there are three observation slots in the indicator bar 18 in the embodiment of the invention shown, it will be seen that each cylinder should be divided into one hundred and two equal horizontal spaces. It should be here understood 25 that the variations of width of these spaces due to the very slight relative difference of diameter of the outermost and innermost cylinders or those intervening, is so very slight as to be negligible and need not be considered. Suitably spaced from the extreme 30 left of the innermost cylinder and at a point in exact radial alignment with each other cylinder is marked a circumferential line 26 in such manner that as it intersects each line 35 25 it forms (preferably) a square major space 27 so that, throughout the course of the line 26, one hundred and two such major spaces are thus formed at the left and 40 around the circumference of each cylinder (see Figure 10). In the center of each of the first one hundred major spaces, on each cylinder, is placed a numeral (designated by the reference character 28). As there are 45 ten cylinders shown and one hundred numbered major spaces on each cylinder, it is apparent that provision is made for one thousand such numerals. The numerals are placed as follows, to wit: one to one hundred 50 on cylinder No. 6, one hundred and one to two hundred on cylinder No. 7, two hundred and one to three hundred on cylinder No. 8, three hundred and one to four hundred on cylinder No. 9, four hundred and one to 55 five hundred on cylinder No. 10, five hundred and one to six hundred on cylinder No. 11, six hundred and one to seven hundred on cylinder No. 12, seven hundred and one to eight hundred on cylinder No. 13, eight 60 hundred and one to nine hundred on cylinder No. 14, and nine hundred and one to one thousand on cylinder No. 15. These major numbers (indicated at 28) are also indicative of one of the numbers being multiplied 65 and cooperate with the bar 18 and the nu-

merals thereon in the proper locating of the desired total in the following manner:—The bar 18 is so mounted and actuated, by mechanism later to be described, that it always lies in very close relation with the 70 particular cylinder being used, to thereby render it impossible to glance upon an erroneous total and to cause the correct total to always appear in the same correct relation to the indicative numeral upon the respective slats 19 of the bar 18. It will also be seen that the bar 18, resting in the position desired has its observation aperture 21 in perfect radial alignment with the indicative numerals 28 so that the latter may be 75 brought to perfect view therethrough (see Figure 10). That area of each cylinder to the right of the major spaces 27 is divided into minor spaces 29, (fifty in number) to correspond with the positioning of the indicative numerals on the slats 19 of the bar 18. These last named spaces are formed by circumferential lines 30 drawn at intervals apart from the line 26. The minor spaces 80 29 are again divided each into three sub-spaces 31 by the longitudinal lines 32 (see Figure 10) and in these last named spaces are inscribed the proper totals in proper relation with the indicative numerals the multiplication whereof they are the results, as 85 shown in said figure. Inasmuch as the full illustration of all of the cylinders is but the compilation of simple multiplication results, it is thought sufficient to illustrate the mode or arrangement of a portion of one of the cylinders and this is done in Figure 10 wherein is shown a portion of the layout of the first or innermost cylinder with the proper relation thereto of the bar (18 being shown by the shaded area). By reference 90 to Figure 10, it will be observed that the width of the bar 18 is approximately equivalent to four of the major spaces 27 and that the mechanism has been properly operated to bring the major spaces of the innermost 95 cylinder, which carries the major numeral "6", to such position as to cause the said numeral to appear through the observation window 21 which indicates that the operator is multiplying "6", by some indicative 100 numeral on the bar 18, say for example the numeral "3" on the upper slat 19. With the parts positioned as shown, the operator glances below the indicative numeral "3" 105 and beholds the correct total to be "18". It will be seen from a careful study of Figure 10 that the result of multiplying any given major number by an indicative number found upon the uppermost slat 19 will 110 be found in the first or uppermost one of the one-third division spaces 31 under that indicative number and to the right of and between the lines 25 confining that major number. To multiply that same major number by a given indicative number on the 115 120 125 130

medial slat 19, the result will be found below the indicative number but in the second or medial one of the one-third division spaces 31 between the lines 25 confining the 5 next succeeding major numeral and to multiply that same first mentioned numeral by a given number on the lowermost slat 19, the result will be found below that indicative number but in the third or lower- 10 most one of the one-third division spaces 31 between the lines 25 confining the second major number subsequent to or below the one we are multiplying. Thus it is that all of the totals of a given major number are 15 not found right in horizontal alignment with the major number being multiplied but part of the same are found under the proper spaces of the two succeeding major numbers or in their proper spaces in the succeeding un- 20 numbered major spaces. Thus it is that the mere relation of the bar 18 and the major number being multiplied causes the correct totals to appear in correct position beneath the indicative numbers on the bar 18.

25 In order to manipulate the parts of the machine to achieve the necessary cylinder and indicator bar shifting for accomplishing the above results, the following mechanism is employed:—For suitably locking the 30 various cylinders to rotate with the central shaft, when the same is manually rotated in a manner soon to be described, a pair of elongated key plates 33—33 are employed to cooperate with the key slot 16 in the cylinder hubs. These keys 33—33 are longitudinally slidably mounted in slots provided for them in the shaft 4 and they are joined at their inner ends by a toggle mechanism 34 in such manner that both keys operate in 40 unison (see Figures 2, 3 and 9). These keys are always in engagement with the slot 16 of the inner cylinder 6 and, therefore, that cylinder rotates whenever the shaft rotates and does not need to be thrust into gear. A 45 bolt 35 is connected to each key 33 and slides in and extends out of the hollow ends of the shaft 4. The bolt 35 at the left hand end of the shaft does not rotate with the shaft but is swivelly connected with the key 4 as 50 at 47. This bolt 35 at the left hand end of the shaft has a stud pin 36 made fast to its projecting end and the said stud has rigid connection with the key actuating mechanism 37 that projects up through the casing or housing face 2, where it is provided with 55 a suitable indicator for designating the point to which it, and the keys connected therewith, should be moved to lock into rotative relation the desired cylinder. It will 60 clearly be seen that by moving this mechanism 37 to the right or left, the keys are moved outward to lock or inward to release the proper cylinder (see Figures 2 and 3). When the proper cylinder has been locked 65 in rotative relation to the shaft, as above de-

scribed, the shaft is now turned in the proper direction to bring to view the proper major number. To provide for the proper rotation of the shaft, it is provided adjacent its left hand end with a small spur gear 38 in mesh with a sliding rack 39 which is operable by a lever 40 projecting through a limiting slot 41 in the side of the housing 1, as will clearly appear by reference to Figures 2 and 4. The rack 39 is slidable in a suitable guide 42. To hold those cylinders stationary, which should not rotate, while the remainder of the cylinders are rotating, I provide a retaining key 43 which is loosely mounted upon the shouldered end of the bolt 35 at the right hand side of the machine and is secured thereto by a nut 44. The key 43 does not rotate with the shaft 35 but is provided with retaining fingers which project through slots provided therefor in the adjacent bearing 5 for the purpose of holding the key against rotation under the urge of the shaft 4. The fingers of the key extend to the cylinder keyways 16 and follow the rotating locking key 33 as it passes out of engagement with and releases from rotation the successive cylinder hubs and thereby holds the cylinders, thus released, from rotation and in proper alignment.

While it is desirable to have the bar 18 project down into the longitudinal slots 17 in the cylinders so as to be in very close proximity with that cylinder being operated, it also follows that the position of that bar must be changed in order to allow another larger cylinder to pass and also to change position to be in proper relation to the last cylinder changed. The automatic effecting of such change of position is accomplished in the following manner:—The projecting end of the left hand bolt 35 (Figure 2) and the extreme right hand end of the retaining key 43 (Figure 3) each have projecting therefrom an extension bar 45 having a cam head 46 that is adapted to engage the cam roller 24 at the respective ends of the bar 18. By reason of the outward and inward sliding action of the said bolts and keys, it is possible to properly adjust the position of the said bar with relation to the cylinder last locked.

Operation.

Assume that the operator desires to multiply the number "43" by the number "3," 120 no setting of the cylinder locking devices need be made since the major number "43" is located in the proper major space at the left of the innermost cylinder 6 and this cylinder always remains in locked relation to the shaft 4 and turns with it. Therefore, to find the desired result, it is only necessary to pull forward on the rack operating lever 40, thereby rotating the innermost cylinder in the direction of the arrow on Fig- 125 130

ure 4. This manual rotation is continued until the desired major number "43" appears through the observation aperture 21 in the bar 18, when the rotation is stopped; 5 with the parts thus positioned, it is only necessary to glance directly below the indicative number "3" on the proper slat 19 and the proper total number "129" will appear.

The same operation is carried out for the 10 calculation of any of the range of results, except that in using the cylinders 7 to 15, inclusive, which carry in series of one hundred each, the major numbers from one hundred and one to one thousand, the operator 15 first manipulates the key actuating mechanism 37 (the same being provided with any suitable means for indicating the cylinder being locked, such as a pointer or finger slideable over a dial) to bring the proper cylinder 20 into rotative relation with the shaft and at the same time holding all of the cylinders of larger diameter out of rotative relation and in proper relation for registering the observation slots 17 thereof. Thus in order 25 to multiply any number from one to one thousand by any number from one to one hundred and fifty, it is only necessary to lock in the particular cylinder carrying the particular major number from one to one 30 thousand, rotate the said cylinder to bring that desired major number into view through the observation window 21 and then glance across and immediately below the particular indicative number located upon 35 one of the slats 19 and by which it is desired to multiply the selected major number to find the correct result of such calculation.

The slideway 41 for the rack lever 40 limits the movements of that lever and it is to 40 be understood that, when the said lever is pushed back to abut the end of said slot farthest from the operator, the parts are in position for holding all of the cylinders with all their observation slots 17 in register (see 45 Figure 4).

From the foregoing description, taken in connection with the accompanying drawings, it is thought the complete construction, operation and advantages of the invention, 50 together with the manner of using the same, will be clear to those skilled in the art to which the invention appertains.

What I claim is:

1. In a calculating machine, a plurality of 55 nested cylinders having suitable indicia on their peripheries and each having a longitudinal slot, an indicator, means for selecting a cylinder and for bringing it into proper corelation with said indicator, the said 60 selecting means including devices for holding stationary the cylinders surrounding the selected cylinder and for moving the remainder of the cylinders with said selected cylinder.

65 2. In a calculating machine, a plurality of

nested cylinders having suitable indicia on their peripheries and each having a longitudinal slot, an indicator movable through said slots, means for selecting a cylinder and for bringing it into proper corelation with 70 said indicator, the said selecting means including devices for holding stationary the cylinder surrounding the selected cylinder and for moving the remainder of the cylinders with said selected cylinder, and cam devices carried by said selecting means and adapted to move the said indicator to co-operate with the particular selected cylinder. 75

3. In a calculating machine, a plurality of 80 nested cylinders having suitably ruled lines and spaces provided with indicia around the periphery of each cylinder and each of said cylinders having a longitudinal slot at its periphery and radial slots merging therewith at the ends of the cylinder, a shaft on which said cylinders are mounted, an indicator cooperating with said cylinders and including a bar to operate in the slots of the cylinders, said bar having indicia to co-operate with the indicia of said cylinders, means for turning said shaft, means for engaging the cylinders at both ends thereof for selectively locking a particular cylinder and those within the same to said shaft, to 90 turn therewith, means for holding the remainder of the cylinders stationary, and means for positioning said indicator bar in the slots of the said cylinders held stationary to cooperate with the particular selected 95 cylinder. 100

4. In a calculating machine, a plurality of nested cylinders having suitably ruled lines and spaces provided with indicia around the periphery of each cylinder and each of said cylinders having a longitudinal slot at its periphery and radial slots merging therewith at the ends of the cylinder, a shaft on which said cylinders are mounted, an indicator cooperating with said cylinders and including a bar to operate in the slots of the cylinders, said bar having indicia to co-operate with the indicia of said cylinders, means for turning said shaft, key devices adapted to engage the cylinders at both ends thereof for selectively locking a particular cylinder and those within the same to the shaft to turn therewith, toggle 110 lever and link devices for causing the keys to turn in unison, means for holding the remainder of the cylinders stationary, and means for positioning said indicator bar in the slots of the said cylinder held stationary to cooperate with the particular selected cylinder. 115

5. In a calculating machine, a plurality of nested cylinders having suitably ruled lines and spaces provided with indicia around the periphery of each cylinder and each of said cylinders having a longitudi- 125

nal slot at its periphery and radial slots merging therewith at the ends of the cylinder, a shaft on which said cylinders are mounted, an indicator cooperating with said cylinders and including a bar to operate in the slots of the cylinders, said bar having indicia to cooperate with the indicia of said cylinders, means for turning said shaft, key devices adapted to engage the cylinders at both ends thereof for selectively locking a particular cylinder and those within the same to the shaft to turn therewith, toggle lever and link devices for causing said keys to move in unison, means for engaging the cylinders at both ends thereof for selectively locking a particular cylinder and those within the same to said shaft to turn therewith, other key devices for holding the cylinders surrounding the selected cylinder stationary, cam devices for positioning said indicator bar in the slots of said cylinders held stationary to cooperate with the selected cylinder, and elements moved by but not rotatable with the locking keys for actuating the said cam devices.

6. In a calculating machine, a casing having a sight opening, a plurality of nested cylinders in said casing, a shaft on which said cylinders are mounted, means to turn said shaft, shiftable key elements carried by said shaft and adapted to connect the selected cylinders to rotate with said shaft while holding the others stationary, said key elements comprising keys slidably on the shaft adjacent each end of the cylinders and adapted to engage key ways in the ends of the cylinders, other keys adapted to engage said key ways at times, means for holding said other keys against rotation with the shaft, means to simultaneously operate all of said keys to lock certain cylinders to the shaft and lock the other cylinders, outside of the selected ones, against rotation, and means to turn said shaft, said cylinders having suitably ruled lines and spaces containing indicia and also having slots in radial alignment which are visible through said sight opening.

7. In a calculating machine, a plurality of nested cylinders each having suitably ruled lines and spaces to provide an annular set or row of major indicia, and a plurality of sets of annular columns and longitudinal rows of minor spaces having minor indicia therein, said cylinders each having a longitudinal slot in its periphery, the slots of the several cylinders adapted to register radially one with another and with said sight opening, and an indicator including a bar adapted to lie in and move radially in said slots to cooperate with a selected cylinder, said indicator bar having slats providing slots and being provided with suitable indicia cooperative with the minor series of indicia of the cylinders and having

a window to expose one of the minor indicia of the cylinders, and means for rotating a selected cylinder to expose its indicia to the slots of the cylinders outside of the selected one, and means to simultaneously set said indicator in the cylinder slots to cooperate with the selected cylinder to expose the major indicia and certain selected rows of minor indicia.

8. In a calculating device, a table comprising a surface provided with suitably ruled lines and spaces providing a vertical row of major spaces to contain major indicia, and a plurality of parallel vertical columns and horizontal rows of minor spaces to contain minor indicia, there being a plurality of horizontal rows of minor spaces for each major space, and an indicator adapted to lie over said surface, said surface and said indicator having a relative movement, said indicator having a window to expose one major space and a number of slots to expose a plurality of minor rows of spaces, there being as many slots in the indicator as there are horizontal rows of minor spaces per major space for the purposes specified.

9. In a calculating device, a table comprising a surface provided with suitably ruled lines and spaces providing a vertical row of major spaces to contain major indicia, and a plurality of parallel vertical columns and horizontal rows of minor spaces to contain minor indicia, there being a plurality of horizontal rows of minor spaces for each major space, and an indicator adapted to lie over said surface, said surface and said indicator having a relative movement, said indicator having a window to expose one major space and a number of slots to expose a plurality of minor rows of spaces, there being as many slots in the indicator as there are horizontal rows of minor spaces per major space for the purposes specified.

10. In a calculating device, a table comprising a surface provided with suitably ruled lines and spaces providing a vertical row of major spaces to contain major indicia, and a plurality of parallel vertical columns and horizontal rows of minor spaces to contain minor indicia, there being a plurality of horizontal rows of minor spaces for each major space, some of which are related to the said major space and others of which are related to others of the major spaces, and an indicator adapted to lie over said surface, said surface and said indicator having a relative movement, said indicator having a window to expose one major space and a number of slots to expose a plurality of minor rows of spaces, there being as many slots in the indicator as there are horizontal rows of minor spaces per major space for the purposes specified.

minor rows of spaces, there being as many slots in the indicator as there are horizontal rows of minor spaces per major space for the purposes specified.

5 11. In a calculating device, a table comprising a surface provided with suitably ruled lines and spaces providing a vertical row of major spaces to contain major indicia, and a plurality of parallel vertical columns 10 and horizontal rows of minor spaces to contain minor indicia, there being a plurality of horizontal rows of minor spaces for each major space, some of which are related to the said major space and others of which are 15 related to others of the major spaces, and an indicator adapted to lie over said surface, said surface and said indicator having a relative movement, said indicator having a window to expose one major space and a 20 number of slots to expose a plurality of minor rows of spaces, there being as many slots in the indicator as there are horizontal rows of minor spaces per major space, the slots of said indicator being adapted to uncover the horizontal rows of minor spaces 25 related to and at the side of the major space whose indicia are exposed through the window of said indicator and those at the side of the adjacent major spaces and related to 30 said exposed indicia.

12. In a calculating device, a table comprising a body having a row of major spaces containing consecutive series of indicating numbers, said body having a plurality 35 of longitudinal and vertical rows of minor spaces at the side of each major space, there being three horizontal rows of minor spaces adjacent to each major space, the top row of which contains in horizontal consecutive 40 series the multiples of the major numbers adjacent thereto, an indicator comprising a bar with a window to expose one major space and with a slot to expose a horizontal rows of minor spaces adjacent to the exposed major space which contains the 45 multiples of the major numbers, said indicator bar being provided with other slots to expose other horizontal rows of minor spaces of two adjacent groups of minor spaces, said 50 indicator having indicating numbers adjacent its slots related to the indicia in the exposed row of minor spaces, all of said minor spaces having suitable indicia substantially as shown and described.

55 13. In a calculating apparatus, a table having suitably ruled longitudinal and transverse lines dividing the table into one hundred and two major spaces arranged in one column and a plurality of minor spaces 60 arranged in groups of three horizontal rows and fifty vertical columns; the first horizontal row of each group containing multiples of the major numbers adjacent thereto, an indicator held over said table and having 65 a window to expose one major number and

having a slot to expose the adjacent rows of multiples of that number, said indicator having two other slots and having indicating numbers along the edges of the several slots running from one to fifty along the first slot, from fifty-one to one hundred along the second slot and from one hundred and one to one hundred and fifty along the third slot, said indicating numbers aligning with the minor spaces of said table exposed, the second slot of said indicator exposing the middle row of minor numbers adjacent to the major numbers next below that major number which shows through the window, while the third slot of said indicator exposes the bottom row of minor numbers adjacent to the major numbers which is second below that major number showing through said window, said second and third exposed rows of minor numbers having indicia corresponding to the product of the major number exposed by the indicator number above the minor number exposed.

14. In a calculating machine, a casing having a horizontal sight opening, a shaft mounted in bearings in said casing parallel to the sight opening, a plurality of nested cylinders having suitable indicia on their peripheries mounted on said shaft and having key ways, a pair of sliding keys on said shaft to turn with the same and adapted to be shifted into locking engagement with one or more of the said cylinders to thereby lock one or more of the said cylinders to the shaft, means for rotating said shaft, means for shifting said keys into and out of position to lock the selected cylinders to the shaft and means for holding the remaining cylinders against rotation with the shaft for the purposes specified.

15. An apparatus of the class described, a plurality of nested cylinders, a shaft held in axial alignment through said cylinders, said cylinders having key ways at their ends, sliding keys mounted on and turning with said shaft, link and lever devices connecting said keys to operate in unison, devices for operating said keys, said cylinders each having a longitudinal slot, the slot of one adapted to register with the slot of another cylinder, an indicator bar movable in said slot toward and from the axis of the cylinders, means for moving said bar in harmony with the movement of the keys whereby said bar will be located in operative relation to the selected cylinders, means for turning the shaft to turn the cylinders engaged by the keys, and another means for holding the unselected cylinders stationary while turning the selected cylinders, said key operating devices including a bolt connecting with one of said keys and longitudinally slidable in the shaft and means for imparting longitudinal movement to said bolt.

16. An apparatus of the class described, a

plurality of nested cylinders, a shaft held in axial alignment through said cylinders, said cylinders having key ways at their ends, sliding keys mounted on and turning with said shaft, link and lever devices connecting said keys to operate in unison, devices for operating said keys, said cylinders each having a longitudinal slot, the slot of one adapted to register with the slot of another cylinder, an indicator bar movable in said slot toward and from the axis of the cylinders, means for moving said bar in harmony with the movement of the keys whereby said bar will be located in operative relation to the selected cylinders, means for

turning the shaft to turn the cylinders engaged by the keys, and another means for holding the unselected cylinders stationary while turning the selected cylinders, said key operating devices including a bolt connecting with one of said keys and longitudinally slidible in the shaft and means for imparting longitudinal movement to said bolt, said indicator shifting mechanism including camming elements connected with said bolt whereby the movement of the bolt will be translated and imparted to said indicator. 20 25
